MOP SQUEEZER PLATE

Norman B. Woleen, Parma Heights, Ohio, assignor to Erie Mop and Wringer Company, Girard, Pa., a corporation of Pennsylvania

Filed Nov. 10, 1961, Ser. No. 67,458

Term of patent 14 years

(Cl. D9—2)

FIG. 1 is a top plan view of a mop squeezer plate, showing my new design;

FIG. 2 is a side elevation thereof;

FIG. 3 is a section on line 3—3 of FIG. 1; and

FIG. 4 is a section on line 4—4 of FIG. 1.

I claim:

The ornamental design for a mop squeezer plate, as shown.
